UNITED STATES PATENT OFFICE.

WILLIAM A. HART, OF LA SALLE, ASSIGNOR TO JOHN E. ROBIE, OF BUFFALO,
NEW YORK.

HANDLE FOR BLOWERS.

SPECIFICATION forming part of Letters Patent No. 338,227, dated March 16, 1886.

Application filed February 24, 1885. Serial No. 156,704. (No model.)

To all whom it may concern:

Be it known that I, WILLIAM A. HART, a citizen of the United States, residing at La Salle, in the county of Niagara and State of New York, have invented a new and useful Lifter for Removing Blowers from Grate-Fires, of which the following is a specification, reference being had to the accompanying drawings, in which—

10 Figure 1 shows the lifter as applied to a blower. Fig. 2 shows the preferred construction of the lifter detached from the blower.

15 My invention relates to an adjustable lifter for removing the blower from before a grate-fire without fear of burning the hands or clothing.

20 It consists of a forked handle of such design that when it is applied to the strap-handle of a blower and slightly depressed it will be locked thereupon, and firmly and securely held, so that the blower can be lifted and safely carried about.

25 In Fig. 1, A is the blower. B is the strap-handle, forming part of the blower, and C is the handle of my blower-lifter as applied.

30 In Fig. 2, C is the handle, terminating in the fork D E E'. F F' are arms at right angles with E E', and slightly inclined toward each other. G G' are points or bearing-surfaces at right angles with F F' and returned toward the handle C.

35 In adjusting the blower-lifter it is held perpendicularly with the fork downward and one of the arms F F' and the corresponding point, G or G', facing the blower. Then by a lateral movement it is passed over the handle of the blower so that one of the points, G, will come in contact with the inside surface of the blower-handle. Then, by bringing the hand to the

front, the other point, G', will come to its position on the other side and inside surface of the blower-handle. Then, by depressing the handle of the lifter, the abutting surface D will be brought to bear upon the outside surface of the blower-handle at a point below where 45 the points G G' touch the blower-handle, thus locking the lifter thereupon. Any lateral movement is prevented by the wings E E'.

40 I believe that the majority of strap-handles on blowers are wedge shape, in which case if 50 the blower-lifter is raised (after having been adjusted and before becoming locked) to a point where the blower-handle is equal in width to the distance between the inside surfaces of the wings E E', additional security is 55 gained.

55 The lifter should be constructed of wire or some other form of metal having a certain degree of flexibility, to allow of a slight bending of the arms F F' inward or outward, so that 60 the points G G' may be properly adjusted to blower-handles varying in size and width.

65 I am aware that detachable handles have been made and used for analogous purposes; but I am not aware that any article of the kind 65 described in this specification has ever been made or used for the purpose designated.

70 I therefore claim as my invention and as a new article of manufacture—

A blower-lifter consisting of a forked handle having the upright bends F F' and the return-bends G G', substantially as and for the purpose described.

WILLIAM A. HART.
